MANUAL CO-AXIAL SWITCH

Donald H. Lanctot, Malibu, Calif., assignor, by mesne assignments, to Electronic Specialty Co., a corporation of California

Filed Jan. 18, 1957, Ser. No. 634,982

9 Claims. (Cl. 333—7)

This invention relates generally to electrical switches and more particularly to manually operable switches for transferring high frequency energy between different co-axial lines.

High frequency co-axial switches are well known in the art and have been provided in a variety of different designs. It is desirable in such switches that connections between one co-axial connector and one of several other connector sections be effected directly without having to switch through the other sections. Further, it is important that cross talk between adjacent co-axial connectors be eliminated. Another desirable feature of such switches is that all of the co-axial connectors to which co-axial lines are to be connected and between which switching connections are to be made, face in the same direction for easy access and simple mounting on control panels. In addition, it is most important that switches for co-axial systems provide a proper impedance match so that no reflections occur in the lines and that they may be substantially dirt and dust proof.

It is a primary object of the present invention to provide an improved manually operable co-axial switch meeting all of the above noted desirable features.

More particularly, it is an object to provide a co-axial switch for transferring electromagnetic energy from a single input co-axial connector to any one of several output co-axial connectors by means of a simple single manual operation.

Another object is to provide a switch of the above type which will automatically return to a neutral position in which no connection is made upon release of the manual operating handle portion of the switch such that the switch of this embodiment "fails-safe."

Still another object is to provide a switch incorporating a slight modification to the above design such that the manually operable portion works on a toggle principle whereby a positive connection is effected once the switch has been moved towards one position or another.

Yet another important object is to provide a manually operable switch which is maintained substantially dirt and dust proof even during successive incremental movements of the switching operation.

These and many other objects and advantages of the present invention are attained by providing a casing having a front face mounting a center and at least two outside co-axial connectors. The inner conductors of these connectors terminate within a chamber interiorally formed within the casing. Resiliently mounted conducting bars are cantilevered within the chamber from the inner conductors of the various outside connectors and extend inwardly towards each other in a position to engage a single contact surface associated with the inner conductor of the central co-axial connector. Suitable push rods are coupled to these conductor bars to move them into and out of contact with the central contact surface upon actuation of a switch arm extending out an opposite face of the casing. The switch arm itself is movably mounted in the casing in such a manner to ex-

clude dirt and dust from the interior chamber through all positions it may assume. The arrangement is such that either a continued pressure is required on the switch arm to maintain one given set of connections or the switch arm structure may be designed to act in accordance with a toggle principle to stay in any definite position to which it is moved. Further, the symmetry of the structure is such that more than two co-axial output connectors may be formed on the front face in a circular pattern about the central co-axial connector whereby a plurality of different types of connections may be made.

The entire structure is not only dust proof, but meets the necessary requirements of impedance matching and excellent isolation between the connectors when not in use.

A better understanding of the invention will be had by referring to the accompanying drawings, in which:

Figure 1 is a perspective view of one embodiment of the co-axial switch of this invention;

Figure 2 is an enlarged elevational cross sectional view of the switch of Figure 1 illustrating the switching components in one position;

Figure 3 is a plan view of the manually operable switch arm portion of the switch illustrated in Figure 2;

Figure 4 is a view similar to Figure 2 illustrating the switching components in another position;

Figure 5 is a plan view of a modified manual switch arm; and,

Figure 6 illustrates a modified component of the switch illustrated in Figures 2 and 4 for providing toggle action.

Referring to Figure 1, one embodiment of the manual co-axial switch of this invention is shown as comprising an outer casing 10 having a cover plate 11 on its rear portion. The cover plate 11 supports a switch arm housing 12 terminating in a round cover 13 containing a slot S from which protrudes a switch arm 14. The opposite face of the casing 10 includes co-axial connectors 15, 16 and 17. Preferably, the central co-axial connector 16 serves as an input connector and the two outside connectors 15 and 17 as output connectors, whereby radiant energy passed into the central connector may be switched to either one of the output connectors depending upon the position of the switch arm 14.

Referring now to Figure 2, the switch arm 14 is shown thrown to the left, and in this particular embodiment, the construction is such that the switch arm must be manually held in the position illustrated in order to maintain a connection. As shown the arm 14 passes inwardly through an annular peripheral bearing surface 18 to terminate in an hemispherical surface 19 adapted to bear against the annular surface 18.

An annular laterally extending flange 20 forms the base of the hemisphere 19 and is arranged to engage a suitable push rod 21 guided within a guide sleeve 22 and biased normally upwardly by a spring 23 all housed within the switch arm housing 12. The lower end of the push rod 21 is coupled to a conductor bar 24 having one of its ends in turn resiliently mounted by a spring 25 to the inner conductor 26 of the co-axial connector 15. The other end of the conductor bar 24 extends inwardly of the casing towards the central co-axial connector 16 and terminates in a position to engage a central contact surface 27 in electrical contact with the inner conductor 28 of the central co-axial connector 16.

Similarly, another portion of the peripheral flange 20 forming an integral part of the hemispherical portion 19 is arranged to engage a second push rod 29 suitably guided by a guide sleeve 30 and biased to an upper position by a spring 31. The lower end of the push rod 29 is coupled to a second conductor bar 32 having its one end in turn resiliently mounted by a spring 33 to

the inner conductor 34 of another outside co-axial connector 17. The inner end 35 of the conductor bar 32 is adapted to engage the conducting surface 27 when in its connected position. As shown in Figure 2, the end 35 of the conductor bar 32 is actually in contact with a second contact surface 36 grounded to the casing top 11 and through the casing 10 to all of the outside conductors of the various co-axial connectors.

A central spring 37 is illustrated within the switch housing 12 and is adapted to bear under the central portion of the annular flange 26 to press the hemispherical surface 19 into continuous contact with the annular surface 18 such that at no time is the interior of the switch arm casing exposed to the exterior.

It will be evident from Figure 2 that in the position shown, the central co-axial connector 16 is in electrical connection with the outside co-axial connector 15. The dimensioning of the conductor bar 24 and the interior portion of the casing 10 is such that a proper impedance match is maintained between the two co-axial connectors. The grounding of the conductor bar 32 as by its end 35 engaging the grounding contact surface 36, on the other hand, completely isolates the output co-axial connector 17 from the other two co-axial connectors. It will also be evident from Figure 2 that the return biasing spring 23 for the push rod 21 exerts an upward force on the annular flange 26 tending to move the switch arm 14 back to a vertical central position. This action is also aided by the central spring 37 inasmuch as the center of the hemispherical surface 19 is substantially co-extensive with the termination pressure points of the spring 37. Therefore, in the operation of the switch illustrated in Figure 2, an intentional manual pressure is continuously applied to the switch arm 14 in order to maintain a connection between the central conductor 16 and either one of the output co-axial connectors 15 or 17.

Figure 3 illustrates in plan view the symmetrical arrangement of the hemispherical guiding annular surface 18 and illustrates in dotted lines the slot S in the cap 13 such that movement of the protruding switch arm is guided in this slot to move in a rectilinear manner.

Figure 4 illustrates the switch of Figure 2 in its second position wherein the central co-axial connector 16 is now connected to the output co-axial connector 17 and the inner conductor of the co-axial connector 15 is grounded. The conductor bar 32 of Figure 2 and also in Figure 4 is dimensioned together with the interior portion of the casing 10 such that a proper impedance match is also maintained between the central connector 16 and outside connector 17 as was the case between the co-axial connectors 16 and 15 when the switch was in the position shown in Figure 2.

In Figure 5 there is illustrated a modified type of top cover 38 provided with two perpendicularly intersecting slots 39 and 40 from the center of which extends a manually operable switch arm 41. In this embodiment, the casing is cylindrical in shape rather than rectangular and there are provided two additional co-axial output connectors disposed in a symmetrical array about the central connector 16. The two slots 39 and 40 serve to guide side-wise and back and forth movements, respectively, of the switch arm 41 such that the central connector 16 may be arbitrarily connected to any one of four output co-axial connectors upon manual movement of the switch arm 41 in the proper direction.

Figure 6 illustrates a modified structure for the switch arm in order to provide a toggle action which modified structure may be readily incorporated in the embodiment illustrated in Figures 2 and 4.

In Figure 6 there is illustrated a switch arm 42 terminating in a hemispherical guiding surface 43 having an annular flange 44 similar to the switch arm 14, hemispherical surface 19 and annular flange 26 of Figure 2. However, the lower portion of the flange 44 includes

an extended spacing element 45 and a central nipple 46 for securingment to the upper end of a control spring 47 analogous to the spring 37 of Figure 2. By spacing the pressure contact point of the upper end of the spring 47 below the center of the hemispherical surface 43, when the switch arm structure as shown in Figure 6 is embodied in the structures of Figures 2 and 4, the pressure exerted by the spring 47, corresponding to the spring 37, will now tend to be overcentered by the distance "d." Thus, once the switch arm 14 is moved towards one position or another, the spring pressure will be such as to throw the switch completely over in a toggle manner.

It is to be particularly noted that the provision of the hemispherical surface 19 and the annular engaging surface 18 completely blocks any dust from entering the switch at any position the switch arm may assume. Further, because of the symmetry of the structure of Figures 2 and 4 about the vertical control axis, more than four output co-axial connectors may be provided all having radially inwardly associated conductor bars. The entire structure is reliable and is capable of long maintenance free use because of the simplicity in the mechanical arrangement of the push rod actuated conducting bars as shown and described. Further, the proper dimensioning of the interior in all respects maintains an excellent impedance match and the grounding out feature of the unconnected output co-axial connectors insures a minimum of cross-talk or interference therebetween and those co-axial connectors in operation.

Various modifications within the scope and spirit of the present invention will occur to those skilled in the art. The invention is, therefore, not to be thought of as limited to the particular embodiments shown for illustrative purposes.

What is claimed is:

1. A co-axial switch comprising, in combination: a casing; co-axial connectors including a center co-axial connector and at least one outside co-axial connector mounted on one side face of said casing, the inner conductors of said connectors extending respectively into said side face to terminate within a chamber in said casing; a conductor bar in said chamber resiliently mounted at one end to the end of one of said inner conductors and having its other end terminating adjacent the end of the other of said inner conductors; a switch arm housing extending from a side face of said casing opposite said one side face, the upper portion of said housing terminating in an opening having an annular bearing surface; a switch arm passing through said opening and terminating in a hemispherical portion adapted to bear against said annular bearing surface such that dirt and dust are blocked from the interior of said housing; an annular flange laterally extending from the base of said hemispherical portion; push rod means having one end adapted to be engaged and longitudinally moved by said flange upon movement of said switch arm, and having its other end coupled to said conductor bar for moving said conductor bar into and out of electrical contact with the end of said other of said inner conductors.

2. A switch according to claim 1, including a central spring in said switch arm housing biasing said hemispherical portion into engagement with said annular bearing surface, the pressure point of action of said spring being substantially co-extensive with the center of the base of said hemispherical portion; and bias means associated with said push rod tending to move said push rod against said flange.

3. A switch according to claim 1, including a central spring in said switch arm housing extending coaxially with said center connector and biasing said hemispherical portion into engagement with said annular surface, the pressure point of action of said spring being spaced from the center of the base of said hemispherical portion whereby

said switch arm is biased to one position when moved towards said position from a center position.

4. A manually operable coaxial switch comprising, in combination: a casing, a center and at least two outside coaxial connectors mounted on one face of said casing and having their inner conductors passing into said casing to terminate in a chamber therein; conducting means in said chamber resiliently mounted to the ends of the inner conductors of said outside coaxial connectors and extending towards each other to terminate adjacent the inner conductor of said center coaxial connector; a switch arm housing extending from a face of said casing opposite said one face and terminating in an opening defined by an annular bearing surface; a switch arm passing through said opening and having an hemispherical portion; spring means within said housing biasing said hemispherical portion into engagement with said annular bearing surface such that dirt and dust are blocked from the interior of said housing and chamber for any position of said switch arm; and at least two push rods extending from said housing on opposite sides of said spring means into said chamber, the respective lower ends of said push rods being coupled to corresponding ones of said conducting means and the respective upper ends of said push rods being positioned for engagement by said switch arm upon canting movement of said switch arm from one side to another whereby either one of said outside coaxial connectors may be electrically connected to said center coaxial connector upon movement of its associated push rod by said switch arm.

5. A switch according to claim 4, in which the interior dimensions of said chamber and the exterior dimensions of said conducting means are such as to provide an impedance match between said center coaxial connector and the outside coaxial connector to which a connection may be made.

6. A switch according to claim 5, including a ground contact secured to said casing in spaced relationship to said end of said inner conductor for said center coaxial connector, said ground contact being adapted to be engaged by any one of said contacting means not in electrical connection with said center coaxial connector whereby that outside coaxial connector not connected to said center coaxial connector is isolated from said center coaxial connector.

7. A switch according to claim 6 in which pressure point of action of said central spring is substantially co-

10

extensive with the center of the base of said hemispherical portion; and bias means associated with each of said push rods tending to move said push rods against said switch arm whereby continual manual pressure on said switch arm is necessary to maintain said electrical connection.

8. A coaxial switch comprising in combination: a casing; coaxial connectors including a center coaxial connector and at least one outside coaxial connector mounted on one said face of said casing, the inner conductors of said connector extending respectively into said side face to terminate within a chamber in said casing, conducting means in said chamber resiliently mounted at one end to the end of one of said inner conductors and having its other end terminating adjacent the end of the other of said inner conductors; a switch arm housing extending from a side face of said casing opposite said one side face, the upper portion of said housing terminating in an opening having an annular and generally spherical bearing surface; a switch arm passing through said opening and having a hemispherical portion adapted to bear against said annular bearing surface such that dirt and dust are blocked from the interior of said housing; push rod means having one end adapted to be engaged and longitudinally moved by said switch arm upon movement of said switch arm and having its other end coupled to said conducting means for moving said conducting means into and out of electrical contact with the end of said other of said inner conductors.

9. A switch according to claim 8 including a central spring in said switch arm housing biasing said hemispherical portions into engagement with said annular spherical bearing surface, the pressure point of action of said spring being substantially coextensive with the center of the base of said hemispherical portion; and bias means associated with said push rod tending to move said push rod against said switch arm.
